(No Model.)

J. N. MILLER.

HANDKERCHIEF EXHIBITOR.

No. 337,422.

Patented Mar. 9, 1886.

UNITED STATES PATENT OFFICE.

JONAS N. MILLER, OF DECATUR, ILLINOIS.

HANDKERCHIEF-EXHIBITOR.

SPECIFICATION forming part of Letters Patent No. 337,422, dated March 9, 1886.

Application filed March 17, 1885. Serial No. 159,153. (No model.)

To all whom it may concern:

Be it known that I, JONAS N. MILLER, a resident of the city of Decatur, county of Macon and State of Illinois, have invented certain new and useful Improvements in Exhibitors for Handkerchiefs, &c., of which the following is a specification.

The object of my invention is to produce an exhibitor for handkerchiefs, &c., that will hold a number of articles in a compact and artistic manner, and which will permit a single article to be removed without disturbing the others and without the necessity of touching the device.

15 My invention consists in a band of suitable size and conformation, together with a series of spring-levers pivoted on the band and adapted to coact with the same for the purpose above specified; and my invention further consists in certain details of construction and combinations of parts, as hereinafter set forth and claimed.

In the drawings accompanying and forming a part of this specification, Figure 1 is an elevation of my device. Fig. 2 is a plan of the same. Fig. 3 is an elevation of the band with the coacting levers removed. Fig. 4 is a plan of Fig. 3. Fig. 5 represents my device in use. Fig. 6 is a perspective view of a lever, and

30 Fig. 7 shows a spring for the lever.

a are the levers. *b* is the band. *b'* is a rim on the band. *c* is a wire on which levers *a* are fulcrumed. *d* are lugs on band *b*, through which wire *c* passes. *e* are springs that operate on the levers to hold them in contact with the lower portion of the band. *g* are supports for the band, attached to plate *f*. *h* is a single pendulous support pivoted in plate *f*, and provided with a suitable attaching device on its

40 upper end.

The lugs *d* are recessed on their under surfaces to receive the wire *c*, and I prefer to stamp said lugs out of band *b*.

The band *b* is represented as circular and of 45 a size to carry a dozen levers; but both the form and size may be varied indefinitely.

The levers *a* are represented as formed of sheet metal and provided with a spring; but different materials may be used, and the lever

50 and spring may be combined in one device.

Supports *h* should be made detachable from plate *f* and of various lengths.

The lower ends of the levers press against the lower surface of the band above the rim, and so form points of support for the handkerchiefs, while the upper ends of the same form surfaces against which power is applied when it is desired to raise a lever with the hands.

As each article is held by a separate lever, there is no difficulty in removing one or more articles without disturbing the others, and the tension of the springs should be so adjusted that an article may be detached by simply pulling the same.

In constructing the device the levers may be placed on the wire and drawn up over the bottom of the band until said wire rests in the lugs and the ends of the levers are above the rim, when the pressure of said ends against said rim will hold the entire series in position. In filling the exhibitor and in removing the articles therefrom only one lever is raised at a time, so that there is no danger of the wire and levers becoming detached from the band.

The modes of constructing the various parts of my device are such as appear to be most expedient; but it is evident that various modifications may be substituted that will effect the same result in a similar manner.

I claim as new and desire to secure by Letters Patent—

1. The multiple clamp for exhibiting handkerchiefs, &c., herein set forth, consisting in a plate or band provided with a rim or elevation, *b'*, and a series of spring-levers pivoted on the band and adapted to operate independently of each other.

2. The combination, in a device for exhibiting handkerchiefs, &c., of a band provided with a series of lugs, a wire extending through the lugs of the band, and a series of spring-levers fulcrumed on the wire and adapted to co-operate with the band, for the purpose set forth.

3. The combination, in a device for exhibiting handkerchiefs, &c., of a band provided with a series of undercut lugs stamped out of said band, a wire extending through the undercut recesses of the lugs, and a series of spring-levers fulcrumed on said wire and

adapted to co-operate with the band, as and for the purpose set forth.

4. The combination, in a device for exhibiting handkerchiefs, &c., of a pendulously-supported band provided with a series of spring-levers adapted to co-operate with the band, as and for the purpose set forth.

5. The combination, in a device for exhibiting handkerchiefs, &c., of a pendulously-supported band adapted to rotate freely in a horizontal plane, and a series of spring-levers ful-

crumed on said band, substantially in the manner and for the purpose set forth.

6. The combination, in a device for exhibiting handkerchiefs, &c., of band *b*, undercut lugs *b'*, rim *d*, wire *c*, levers *a*, and springs *e*, as and for the purpose set forth.

JONAS N. MILLER.
